(57) **CLAIM**

The ornamental design for a package for a portable incendiary apparatus, as shown and described.

DESCRIPTION

FIG. 1 is a top perspective view of a package for a portable incendiary apparatus in accordance with the invention, shown in one embodiment;

FIG. 2 is a front side elevational view of the package shown in FIG. 1;

FIG. 3 is a rear side elevational view of the package shown in FIG. 1;

FIG. 4 is a top plan view of the package shown in FIG. 1; FIG. 5 is a bottom plan view of the package shown in FIG. 1;

FIG. 6 is a right end elevational view of the package shown in FIG. 1;

FIG. 7 is a left end elevational view of the package shown in FIG. 1;

FIG. 8 is a top perspective view of a package in accordance with the invention, shown in another embodiment;

FIG. 9 is a front side elevational view of the package shown in FIG. 8;

FIG. 10 is a rear side elevational view of the package shown in FIG. 8;

FIG. 11 is a top plan view of the package shown in FIG. 8; FIG. 12 is a bottom plan view of the package shown in FIG. 8;

FIG. 13 is a right end elevational view of the package shown in FIG. 8; and,

FIG. 14 is a left end elevational view of the package shown in FIG. 8.
